UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Original application filed September 28, 1920, Serial No. 413,378. Divided and this application filed December 19, 1921. Serial No. 523,498.

To all whom it may concern:

Be it known that I, DAVID S. KENNEDY, a citizen of the United States, residing at Brooklyn, in the county of Kings and State 5 of New York, have invented certain new and useful Improvements in Typographical Distributing Machines, of which the following is a specification, reference being had therein to the accompanying drawing, 10 being a division of an application filed by me Sept. 28th, 1920, Serial No. 413,378.

My invention relates to typographical machines, such as linotype machines of the general organization represented in U. S. 15 Letters Patent to O. Mergenthaler No. 436,532, wherein circulating matrices are released from a magazine in the order in which their characters are to appear in print and then assembled in line, the composed line transferred to the face of a slotted mold, the mold filled with molten metal to form a slug or linotype against the matrices which produce the type characters thereon, and the matrices thereafter 20 returned through a distributing mechanism to the magazine from which they started.

The present improvements are directed more particularly to the distributing mechanism of such machines, and involves a new 30 arrangement for sorting or separating matrices of two different sets, whether said sets constitute entirely distinct fonts or different portions of the same font. According to the scheme contemplated, the matrices 35 of one set are formed with projecting ears located at the right side of the matrix bodies, while those of the other set are formed with projecting ears located at the left side of the matrix bodies, and means 40 are provided to cooperate with the matrices while in course of distribution and deliver them at different points according to the location of their projecting ears. The exact construction and arrangement of the 45 parts will be best understood from the detailed description to follow.

Referring to the drawings:

Fig. 1 is a side elevation of the upper portion of a linotype machine presenting an 50 embodiment of my invention;

Fig. 2 is a front view of certain portions of the primary distributor therein employed;

Figs. 3 and 4 are sections taken on the

line $x-x$ of Fig. 1, and showing matrices 55 in course of distribution; and

Fig. 5 is a view of two matrices taken from the different matrix sets and formed with different or unlike tooth-combinations.

The matrices X and Z illustrated in Fig. 60 5 are representative of the two different matrix sets herein employed. As will be observed, the matrix X is of the same form as heretofore, being formed at its upper end with the customary tooth combination X^1 65 and on its opposite edges with the usual projecting ears X^2 , which latter as before are located at the right side of the matrix body (the following side during composition and the leading side during distribution). The matrix Z is likewise formed at its upper end with a tooth combination Z^1 70 and on its opposite edges with projecting ears Z^2 , and differs from the matrix X only in respect to the location of its projecting 75 ears Z^2 , which in this instance are located at the left side of the matrix body.

In the embodiment illustrated, the matrices X are stored in the lower magazine 80 E , and the matrices Z in the upper magazine F , which magazines are connected by means of the magazine entrances G and H to the separate secondary distributors J 85 and K , respectively. These parts may be of any desired construction, such for example as embodied in the commercial machines of this class, in which each magazine is formed with ninety different matrix channels and the cooperating distributor with as many different tooth combinations, 90 and in which the matrices stored in the magazines are ordinarily of different fonts. My present improvements contemplate an improved form of mechanism by which matrices from the two magazines are first 95 separated according to form or font and then delivered to their appropriate secondary distributors. In the present instance, I employ a primary distributor which simply comprises a short bar or rail L of customary V-shape in cross-section and a set 100 of conveying screws M for propelling the matrices therealong. This bar L is provided as usual with the full complement of ribs or teeth L^1 to cooperate with the 105 tooth combinations of the matrices, but these teeth L^1 (unlike those of the ordinary primary distributor bar) are continuous

100
105

throughout so as to release the matrices of both sets at a common point. Thus, taking the two matrices shown in Fig. 5 by way of example, although their respective tooth 5 combinations X^1 and Z^1 differ, both will be released from the bar L at the same point, due to the continuous character of the ribs L^1 which maintain their engagement with the tooth combinations of the matrices until 10 the latter have completely traversed the bar. Accordingly, each matrix of each set, irrespective of its particular tooth combination, is released from the bar L at the same point. As the matrices are released from 15 the bar L , they drop directly into two underlying tubes or conductors N and O which are constructed to guide the matrices by their projecting ears, each tube having its edges bent over to provide grooves wherein 20 the matrix ears engage and being open at one side to allow the matrix body portions to project outwardly therefrom. As shown in the several figures, these two tubes are arranged with their open sides facing each 25 other, being straight and disposed in immediate contact at their upper ends for a distance equal at least to the length of a matrix, and then curved forwardly and backwardly to make connection with the 30 respective secondary distributors. It may also be noted that the tube N is offset laterally from the tube O at or near the point where the two diverge so as to allow the matrices to pass therealong without interference. 35

According to the above construction and arrangement of the parts, the matrices of both sets are all released from the bar L at a common point, and then dropped directly 40 into the two tubes as permitted by the open character of their opposing sides, becoming engaged with one or the other of the two tubes according to the location of their projecting ears. That is to say, a matrix Z 45 (which has its ears Z^2 located at the left side) will be carried along the tube O to the distributor K ; while a matrix X (which has its ears X^2 located at the right side) will be carried along the tube N to the distributor J . In this way, the matrices of the respective sets are separated from each other and then restored to their corresponding distributor for return to the appropriate magazine. 50

55 The foregoing embodiment has been illustrated merely by way of example and as applied to one class of machines, and it will be obvious that the invention is susceptible of many other modifications and alterations 60 which will still be comprised within its spirit. For instance, an arrangement similar to that described might be employed in distributing sorts matrices into different receptacles, which result could be accomplished 65 by modifying the sorts matrices in the above

manner and arranging the two tubes so as to receive them from any selected point of the distributor, say the extreme end of either of the two secondary distributor bars J and K . Again, by employing a series of tubes N and O , the matrices of the two sets might be distributed into a pair of superposed magazines directly from a single distributor bar, which arrangement would involve merely the use of a pair of such tubes in connection 75 with each tooth combination of the ordinary distributor bar. Many such variations and adaptations of my invention will readily suggest themselves to those skilled in the art without departure from its scope. I therefore desire it to be understood that I do not limit myself to any specific form or arrangement except in so far as such limitations are specified in the claims. 80

Having thus described my invention, its 85 construction and mode of operation, what I claim is as follows:

1. In a typographical distributing machine equipped with matrices, each formed with projecting ears on its opposite edges, the 90 combination of means for releasing matrices at a given point, and a pair of tubes or conductors arranged to receive the matrices directly as they are so released and constructed to guide them by their projecting ears, 95 the said ears being located at the left side of some and at the right side of other of the matrices so as to enable said matrices to enter one or the other of the two tubes or conductors according to the location of their 100 projecting ears.

2. In a typographical distributing machine equipped with two sets of matrices, each formed with projecting ears on its opposite edges, the combination of a primary 105 distributor constructed to release the matrices of both sets at a common point, two secondary distributors, and a pair of intermediate tubes or conductors arranged to receive the matrices directly as they are released from the primary distributor and deliver them to the respective secondary distributors, the said tubes or conductors being constructed to guide the matrices by their projecting ears, and the said projecting ears 110 being located at the left side of the matrices of one set and at the right side of the matrices of the other set so that said matrices may enter one or the other of the two tubes or conductors according to the location of 115 their projecting ears.

3. In a typographical distributing machine equipped with two sets of matrices, each formed at its upper end with a tooth combination and on its opposite edges with 120 projecting ears, the combination of a primary distributor including a V-shaped distributor bar formed with continuous ribs to cooperate with the tooth combinations of the matrices and release them at a common 125 130

point, two secondary distributors each including a V-shaped distributor bar formed with a series of tooth combinations to cooperate with those of the matrices and release them at different points in the length thereof, and a pair of tubes or conductors arranged to receive the matrices directly as they are released from the primary distributor and deliver them to the respective secondary distributors, the said tubes or conductors being constructed to guide the matrices by their projecting ears, and the said ears being located at the left side of the matrices of one set and at the right side of the matrices of the other set, so that said matrices may enter one or the other of the two tubes or conductors according to the location of their projecting ears.

4. In a typographical distributing machine equipped with matrices, each formed with projecting ears on its opposite edges, the combination of a distributor bar for releasing matrices at a given point, and a pair of tubes or conductors arranged to receive the matrices directly as they are so released and constructed to guide them by their projecting ears, the said ears being located at the left side of some and at the right side of other of the matrices so as to enable said matrices to enter one or the other of the two tubes or conductors according to the location of their projecting ears.

In testimony whereof, I have affixed my signature hereto.

DAVID S. KENNEDY.
